(57) **CLAIM**

The ornamental design for a blade for a solar shade, as shown and described.

DESCRIPTION

FIG. 1 is a perspective view of a blade for a solar shade, showing our new design;

FIG. 2 is a front top view thereof;

FIG. 3 is a right view thereof;

FIG. 4 is a front view thereof;

FIG. 5 is a bottom view thereof; and,

FIG. 6 is a left view thereof.

The broken lines showing portions of the blade for a solar shade form no part of the claimed design.
